GASEOUS ELECTRIC DISCHARGE DEVICE

Cornelis Bol, Eindhoven, Netherlands, assignor
to General Electric Company, a corporation of
New York

Application May 16, 1933, Serial No. 671,318
In the Netherlands June 30, 1932

7 Claims. (Cl. 176—123)

The present invention relates to gaseous electric discharge devices generally and more particularly the invention relates to improvements in such devices in which a condensable metal vapor 5 forms the gaseous filling or is a component of the gaseous filling, similar to the devices described in my co-pending application Serial No. 644,099, filed November 23, 1932.

In the co-pending application referred to above 10 the stem parts of the container of the gaseous electric discharge device are closed off from the part of said container surrounding the discharge path. Undesired condensation of the metal vapor around the stem parts of the devices, which are 15 the coolest parts of the device, is thus avoided and the vapor pressure of the condensable metal corresponds to the temperature of the container rather than to that of the cooler stem parts of 20 said container. Where the walls of the container are at a proper temperature the condensable vapor is maintained in vaporous condition in the discharge path during the operation of the device even though the stem parts of the container are at a lower temperature. When an 25 alkali metal, such as sodium, is used as the source of the condensable vapor in such a device it is practical to make the parts of said container surrounding the discharge path of a glass resistant to the chemical effects of the metal vapor and 30 the stem parts of a different glass having better sealing characteristics than said resistance glass since the stem parts are protected from the metal vapor during the operation of the device.

Although gaseous electric discharge devices of 35 the type described above are successful in operation some difficulty has been experienced in evacuating the containers thereof during the manufacture of the devices. The object of the 40 present invention is to provide a gaseous electric discharge device the gaseous atmosphere of which consists wholly or in part of condensable metal vapor in which evacuation of all parts of the container of the device is easily accomplished 45 during the manufacture of the device and in which the stem parts of said container are closed off from the other parts of said container during the 50 operation of the device. Still further objects and advantages attaching to the device and to its use and operation will be apparent to those skilled in the art from the following particular description and from the appended claims.

The above object is attained by providing a long, narrow communicating passage connecting the part of said container surrounding the discharge path and the stem parts of said con-

tainer. It is preferable that the greater part of the length of said passage be located in the cooler stem parts of said container. During the manufacture of the device all parts of the container thereof can be evacuated to the degree desired 5 because of the communicating passage. The diameter of the long passage is preferably less than the length of the mean free path of the ionized gas particles and a capillary tube is preferable, so that the rate of flow of the vapor there- 10 through is reduced to a minimum. During the first few hours of operation of the device the few ionized metal particles that do penetrate into the part of said passage located in the cooler stem part of said container condense therein and 15 the deposits of condensed material on the walls of the passage close said passage so that the stem parts of said container are closed off from the other parts of said container during the re- 20 mainder of the operating life of the device.

In the drawing accompanying and forming 25 part of this specification an embodiment of the invention is illustrated, in which

Fig. 1 is a side elevational partly sectional view of an electric discharge device embodying one 25 form of the present invention, and

Fig. 2 is a detail sectional view of the stem part 30 of a gaseous electric discharge device embodying another form of the invention.

Referring to Fig. 1 of the drawing the new and 35 novel gaseous electric discharge device comprises a light transmitting container 1 made of a glass 35 resistant to the chemical effects of the gaseous filling therein. Electrodes 4 and 5 are sealed into said container 1 and the electrode inleads 40 therefor are sealed into the pinch part 2 of the stem 3. Said stem 3 is, when desired, made of a different glass than said container 1 and of a glass having better sealing characteristics than said resistant glass. Said electrode 4 is the cath- 40 ode, said cathode 4 consists of a metal filament, such as a tungsten filament, coated with an electron emitting material, such as barium oxide, and is electron emitting when heated. Said electrodes 5 are plate shaped anodes and are arranged on 45 either side of said cathode 4. The part of said container 1 surrounding said electrodes 4 and 5 has a gaseous filling therein comprising a condensable gas, such as a mixture of neon at approximately 1 mm. pressure and sodium, or a 50 mixture of argon and sodium. The sodium which is solid at room temperature and from which the sodium vapor is generated by the heat of the discharge between said electrodes 4 and 5 during the 55 operation of the device is located in that part of

said container surrounding the discharge path between said electrodes 4 and 5.

The part of said container 1 surrounding said stem 3 and said stem 3 are the coolest portions of said container 1 during the operation of the device. The septum 6 closes off the cooler stem parts 3 of the container 1 from the part of said container 1 surrounding the discharge path between said electrodes 4 and 5. Said septum 6 consists of a heat insulation material resistant to the chemical effects of the gaseous filling, such as mica, glass, or the like and is a circular disc the diameter thereof corresponding to or closely approaching that of the inner walls of that part 15 of container 1 surrounding said stem 3. The current inleads for said electrodes 4 and 5 pass through said disc 6. Said disc 6 rests on top of the pinch part 2 of said stem 3 and is forced against the lower part of a circular indentation 7 in the walls of said container 1. The space, if any, between the rim of said disc 6 and the inner wall of said container 1 is sealed by a body 8 of suitable sealing material, such as a mixture of talcum and water glass.

If the spaces above and below the septum 6 were completely divided during the manufacture of the device it would be difficult to evacuate all parts of the container 1 through a single exhaust tip. For this reason the tube 9, made of insulation material, such as magnesium oxide, is provided to connect the spaces on both sides of said container 1. The greater part of the length of said tube 9 is located in the space about said stem part 3 and part of the outer wall of said tube 35 9 is contiguous to the wall of said stem 3. The part of said septum 6 through which said tube 9 passes fits tightly around said tube 9 and a suitable soldering material, such as a mixture of talcum in water glass, is used to hold said tube 9 against the wall of said stem 3. The tube 9 is thus held rigidly in position in said container 1. The diameter of the passage in said tube 9 is approximately the same as the length of the mean free path of an ionized gas particle and said tube 40 9 is of the nature of a capillary tube. Though the length of tube 9 is optional depending on the type of container it is advantageous but not essential that the tube 9 have a length of at least 5 times the diameter of the passage therein and a greater length is advisable in many instances. I prefer a tube of 1 sq. mm. cross section and 2 cm. in length.

Having the above structure the spaces above and below the septum 6 can be evacuated through a single exhaust tip communicating with either one of said spaces which simplifies the manufacture of the device.

The device is started into operation by heating the cathode 4 to an electron emitting temperature. Voltage is then applied across the terminals of said electrodes 4 and 5 to start the discharge between said electrodes 4 and 5. At first this discharge is conducted between said electrodes 4 and 5 by the neon. The heat of the discharge vaporizes the sodium, which is solid at room temperature, and the light emitted by the device is rich in rays characteristic of the sodium vapor. The flow of sodium vapor through the passage in said tube 9 during the operation of the device is reduced to a minimum due to the small diameter and long length of said passage. Part, or all of the metal vapor that does pass through said tube 9 condenses on the cooler lower wall thereof contiguous and adjacent to the stem 70 3. After the device has been operating a few

hours deposits of this condensed material completely closes the narrow passage in said tube 9 and the spaces above and below said septum 6 are completely divided. The advantages of this division of the space surrounding the discharge path between the electrodes 4 and 5 from the space about the stem 3 have been pointed out above.

Another embodiment of the invention is illustrated in Fig. 2 of the drawing. This embodiment is similar in all respects to the embodiment illustrated in Fig. 1 except that the septum is a metal disc 10 made of nickel or chrome-steel, for example. Said disc 10 is slightly dished so that it is somewhat flexible to allow for the expansion and contraction of the walls of the container into which the rim parts of said disc are fused. A layer 11 of glass resistant to the chemical effects of the metal vapor in the part of the container surrounding the discharge path 20 in the device is applied to the surface of said disc 10 facing the gaseous electric discharge path in the device to protect said disc 10 from the chemical effects of said metal vapor. Four round openings are provided in said disc 10 to accommodate insulating tubes 12 and 13 made of magnesium oxide, for example. Said tubes 12 and 13 are attached to said disc 10 by flowing the glass of layer 11 into the openings between the sides of said tubes 12 and 13 and the sides of 30 the openings in said disc 10 which also closes said openings in said disc 10. The electrode inleads 14 are sealed into an inverted stem 15 and are led through said tubes 12 and 13. Said tubes 12 fit tightly around the electrode inleads 14 35 therein. A slight play is present between the inner wall of the tube 13 and the inlead 14 in said tube 13. The lower end of said tube 13 terminates a distance from the stem 15 while the lower ends of said tubes 12 are fused into said 40 stem 15. The passage in said tube 13 connects the spaces above and below the disc 10 so that both spaces are exhausted through a single exhaust tip during the manufacture of the device. During the first few hours of operation of the 45 lamp device the passage 13 is closed by deposits of condensed material therein as the lower part of said tube 13 is colder than the upper part thereof during the operation of the device. A 50 complete separation of the space above and below the disc 10 is thus effected with the operating advantages heretofore pointed out.

During the operation of the above described gaseous electric discharge lamp devices that part of the walls of the container 1 surrounding the discharge path is maintained at a temperature higher than the condensing temperature of the condensable gas by the high current density discharge between the electrodes made possible by the use of a thermionic cathode 4, or by reducing 60 the rate of the radiation of heat from the walls of said container 1 to a minimum by an evacuated bulb enclosing the container or by a double walled, evacuated jacket, for example, or a combination of these methods is used, when desired. 65

While I have shown and described and have pointed out in the annexed claims certain novel features of the invention, it will be understood that various omissions, substitutions and changes in the forms and details of the device illustrated 70 and in its use and operation may be made by those skilled in the art without departing from the broad spirit and scope of the invention.

What I claim as new and desire to secure by Letters Patent of the United States:— 75

1. An electric discharge device comprising a container, electrodes sealed therein, a gaseous filling therein comprising a condensable gas, a stem fused to said container, a septum between the part of said container surrounding the discharge path between said electrodes and the stem part of said container, and a capillary tube through said septum. 5
2. An electric discharge device comprising a container, electrodes sealed therein, a gaseous filling therein comprising a condensable gas, a stem fused to said container, a septum between the part of said container surrounding the discharge path between said electrodes and the stem part of said container, and a capillary tube through said septum, the greater part of said capillary tube being in the stem part of said container. 10
3. An electric discharge device comprising a container, electrodes sealed therein, a gaseous filling therein comprising a condensable gas, a stem fused to said container, a septum between the part of said container surrounding the discharge path between said electrodes and the stem part of said container, and a capillary tube through said septum, the greater part of said capillary tube being in the stem part of said container and contiguous to said stem. 15
4. An electric discharge device comprising a container, electrodes sealed therein, a gaseous filling therein comprising a condensable gas, a stem fused to said container, a septum between the part of said container surrounding the discharge path between said electrodes and the stem part of said container, said container and said septum being of a material resistant to the chemical effects of said gaseous filling, said stem being of a different material and a capillary tube through said septum. 20
5. An electric discharge device comprising a container, electrodes and electrode leads sealed therein, a gaseous atmosphere therein, a stem fused to said container, a septum between the part of said container surrounding the discharge path between said electrodes and the stem part of said container, a tube of small diameter extending through said septum, said tube surrounding one of said electrode leads and having an inside diameter larger than the diameter of said lead. 5
6. An electric discharge device comprising a container, electrodes and electrode leads sealed therein, a gaseous atmosphere therein, a stem fused to said container, a septum between the part of said container surrounding the discharge path between said electrodes and the stem part of said container, said septum being a flexible disc fused to the walls of said container, a tube of small diameter extending through said septum, 20 said tube surrounding one of said electrode leads and having an inside diameter larger than the diameter of said lead. 15
7. An electric discharge device comprising a container, electrodes sealed therein, a gaseous atmosphere therein, a stem fused to said container, a septum between the part of said container surrounding the discharge path between said electrodes and the stem part of said container, a vaporizable material in the part of said container surrounding the discharge path between said electrodes and a communicating passage between the stem part of said container and the part thereof surrounding the discharge path, the cross-section of said passage being such that 30 deposits of condensed metal vapor close said passage during the operation of the device. 35
